UNITED STATES PATENT OFFICE.

JAMES H. VAN NESS AND MORTIMER A. BLAND, OF CHARLOTTE, N. C.

ELECTRO-MAGNETIC DENTAL PLUGGER.

SPECIFICATION forming part of Letters Patent No. 310,099, dated December 30, 1884.

Application filed August 28, 1884. (No model.)

To all whom it may concern:

Be it known that we, JAMES H. VAN NESS and MORTIMER A. BLAND, of Charlotte, in the State of North Carolina, have invented certain new and useful Improvements in Electro-Magnetic Dental Pluggers or Mallets, of which the following is a specification.

Our invention has reference to that kind of an electro-magnetic dental plunger or mallet which is operated through the instrumentality of an automatic circuit-breaking device.

Heretofore, so far as we are informed, the circuit-breaker has been mounted on and carried by the instrument, forming, in fact, an integral part of it. There are a number of objections to such an arrangement. The main disadvantage is the buzzing sound produced by the circuit-breaker, which, being in close proximity to the patient, is extremely annoying. Furthermore, the instrument is somewhat complicated as a whole, and it is difficult to obtain the needed range of adjustment of the stroke of the mallet.

With a view of obviating these and other objections, we have devised our improvement, the main characteristics of which reside in the fact that the automatic circuit-breaker is distinct and separate from the mallet or plunger, having no mechanical connection therewith, the only connection between the two being electrical, and such as afforded by the circuit-wire. In this way we are enabled to locate the circuit-breaker at any distance from the patient, even placing it in the next room, or in any other part of the building, as desired.

The system in which our invention is embodied comprises a severed circuit, a circuit-closing key, an electro-magnetic dental plunger or mallet, an automatic circuit-breaker independent of and separate from the said mallet or plunger, and connections whereby, when the circuit is closed by the key, the current from the generator or source of electricity will be directed alternately through the electro-magnet of the circuit-breaker and the electro-magnet of the plunger or mallet.

Our invention will be readily understood by reference to the accompanying drawing, which, to some extent, represents diagrammatically the system hereinbefore referred to.

We have not deemed it necessary to repre-

sent in detail the special construction of the dental plunger or mallet, for it can be, and is in practice, similar to those now in use, save that it does not contain an automatic circuit-breaker.

A represents the battery or source of electricity, B the automatic circuit-breaker, C the electro-magnetic dental plunger or mallet, and D the circuit-closing key. In practice the circuit breaker and battery are usually located in one room, while the plunger or mallet and circuit-closing key are in the room in which the patient is to be operated on, and in convenient proximity to the operating-chair. The circuit-closing key is spring-acting, and normally in position to maintain the circuit broken, and generally is so placed that it may be conveniently pressed by the foot of the operator to close the circuit. The circuit-breaker consists of an electro-magnet, a, an armature, b, carried by an adjustably-weighted pivoted lever, c, which normally tends to hold the armature away from its magnet. The armature-lever has a small laterally-projecting arm, c', which engages the forked end of a vibratory elbow-lever, d, pivoted at d', and provided at its upper end with a contact-strip, e, which plays between the contact-points f, g.

The circuit connections are as follows: Pole N of the battery is connected by wire 1 to the contact-strip e. The other pole, S, of the battery is connected by the wire 2 to the circuit-breaking electro-magnet a, and thence by wire 3 to the key D. The point 4, which the key makes contact with in order to close the circuit, is connected by wire 5 to the contact-point g. From contact-point f leads a wire, 6, which connects with one end of the helix of the plunger-magnet, the other end of which is connected by wire 7 to wire 2. Normally the contact-strip e is in contact with g.

The drawing shows the position which the parts assume when the circuit is open. When by means of the key D the circuit is closed, the operation is as follows: The circuit is first through the wire 5, contacts g f, wire 1, battery A, wire 2, electro-magnet a, wire 3, back to the circuit-closing key D. The magnet a is thus energized and attracts its armature b with the effect of vibrating the lever d in a direction to cause the strip e to break contact.

with *g* and to make contact with *f*. This cuts out the circuit-breaking magnet *a*, and the circuit is from the battery through wire 1, contacts *e f*, wire 6, the helix of the plugger, wires 7 and 2 back to battery. The magnet *a* being cut out, its armature drops back to the position indicated in the drawing, breaking the circuit *e f* and reinstating it through *e g*, thus cutting out the plugger-magnet. In this way so long as the circuit is closed by means of the circuit-closing key *D* the circuit is completed alternately through the circuit-breaking magnet and the plugger-magnet, thus producing the effect desired in this class of dental instruments.

We have described what we believe to be, on the whole, the best embodiment of our invention. We do not, however, wish to be understood as restricting ourselves to the special devices or arrangement of the same herein represented, for it is manifest that the same may be varied in many particulars without departure from the spirit of the invention.

What we claim as new and of our own invention is--

1. The combination, in an electric circuit, of an electro-magnetic plugger or mallet and an automatic circuit-breaker for operating the same mechanically and independent of and separate from said mallet, but electrically connected therewith, substantially as and for the purposes hereinbefore set forth. 30

2. The combination, in a circuit, of a circuit-closing key, an electro-magnetic dental plugger or mallet, an automatic circuit-breaker independent of and separate from said mallet, and electrical connection, substantially as described, whereby the circuit, when closed by the key, is completed alternately through the magnet of the circuit-breaker and magnet 40 of the mallet, substantially as and for the purposes set forth.

In testimony whereof we have hereunto set our hands this 18th day of August, 1884.

JAMES H. VAN NESS.
MORTIMER A. BLAND.
